UNITED STATES PATENT OFFICE.

DAVID PETRI-PALMEDO, OF BRIDGEPORT, CONNECTICUT, ASSIGNOR TO ELECTRIC COMPOSITOR COMPANY, OF NEW YORK, N. Y., A CORPORATION OF NEW JERSEY.

SPACE-BAND-RELEASING MECHANISM FOR TYPE-BAR MACHINES.

1,176,981.

Specification of Letters Patent. Patented Mar. 28, 1916.

Application filed June 4, 1914. Serial No. 842,859.

To all whom it may concern:

Be it known that I, DAVID PETRI-PALMEDO, a citizen of the United States, residing at Bridgeport, in the county of Fairfield and 5 State of Connecticut, have invented a certain new and useful Improvement in Space-Band-Releasing Mechanism for Type-Bar Machines, of which the following is a full, clear, and exact description.

10 This invention pertains to type bar machines of familiar construction,—that is machines in which a type bar is cast from a line of justified matrices which are assembled in said machine and are spaced and 15 justified by means of double wedge space bars of generically well known construction.

The invention relates particularly to the means whereby said space bars are released one by one, and are allowed to fall onto the 20 assembling rail behind the last matrix assembled thereon.

25 The object of the invention is to provide this so-called space bar escapement mechanism in a form which shall be durable and certain in its action; and the invention consists in the construction and combination of parts which are shown in the drawing and hereinabove described and definitely pointed out in the appended claims.

30 In the drawings, Figure 1 is a front view of said invention when the mechanism in front of the space bands has been removed, and the space band releasing slide and the cover therefor are sectioned. This view shows the parts in their normal position.

35 Fig. 2 is a similar view, except that the space band releasing slide and the end space band have both been raised to positions such that said space band is about to drop. Fig. 3 is

40 a view of the spacer magazine from the right end thereof and a space band therein when the releasing slide and cover plate have been removed. Fig. 4 is a magnified plan view of the right end of the space band magazine

45 and the space band escapement mechanism and a space band, the parts being shown in the same relative positions which they occupy in Fig. 2. Fig. 5 is like Fig. 1, except that the parts are greatly magnified. Fig. 6

50 is a top plan view of the space band releasing slide. Fig. 7 is a front view thereof; and Fig. 8 is a view from the left side thereof, as shown in Figs. 1, 2 and 5.

55 Before beginning a description of the so-called space band escapement mechanism, it

is thought desirable to call attention to certain features of construction of the space bands themselves, not because these features are novel, but in order that one may better understand how the present invention is caused to operate in the manner and with the results hereinafter stated. Each space band comprises a short wedge 2, and a long wedge 3, which are permanently connected in such wise that the long wedge may be moved upward relative to the short wedge for the purpose of effecting the justification of matrix lines. The short wedge has adjacent its lower end two oppositely extended ears 2^a; and the long wedge has in its lower edge the vertical notch 3^a. The space bands hang from these ears 2^a when the space bands are in the so-called space band magazine, and when in various other parts of the machine.

The space band magazine so-called consists of two parallel inclined rails 13, which are, for most part, the lower walls of downwardly inclined grooves 12, which are formed in the opposed faces of two parallel rail plates 10 which are fixed to suitable frame members 14. These rails 13 at their lower ends are made to extend to the right slightly beyond the vertical edges of the right ends of the rail plates 10 and of the frame members 14 by which they are supported. But these extensions 13^a of the rails 13 are quite narrow and project beneath only parts of the ears,—that is to say, the parts of the ears which are close to the body of the space bar. In other words, the outer ends of these ears project beyond these extension rails 13^a, as clearly seen in Figs. 4 and 5.

There are two space band lifters 16. Each of these has at its upper end a horizontal portion 16^a, which normally lies beneath the outer end of the associated ear on the lowest or foremost space band, and a beveled portion 16^b which normally lies below the outer end of the adjacent ear of the second space band. These two lifters are simultaneously movable up and down. To make sure that these two lifters shall move up and down together, and in order to secure some other advantages which will be apparent, these lifters are formed as integral parts of a slide 17, which slide is mounted in a guide-way formed between the right ends of the frame members, 14, and a vertically grooved cover plate 25 fixed thereto. This slide has

along its front and rear edges, and extending to the left therefrom, the vertical flanges 17^a. The lifters 16 are formed as vertical ribs projecting forwardly and backwardly 5 respectively from these two flanges 17^a. This is perhaps an awkward way of describing the slide and its integral parts, as shown; but this manner of describing it has the advantage of calling particular attention to the fact that the invention, broadly 10 considered, does not require that these space band lifters be parts of a slide.

Having regard merely for the slide itself, irrespective of its primary function of imparting simultaneous up and down movement to the lifters, said slide consists of a metal plate which has a vertical undercut groove 17^d formed in its left face, extending from its lower end upward to a point which 20 is normally slightly below the lowest parts of the extension rails 13^a. At its upper end 17^c this slide is quite thin, and the left face of this thin part is a material distance to the right of the left face of the slide, regarded as a whole. The space band lifters 16 are the overhanging vertical flanges of the vertical groove in said slide. With a slide so formed, these lifters not only serve the purpose of lifting the space bands one 30 by one, but also serve as the left wall of the groove or channel 17^b down which the space bands fall, and by which they are guided so as to fall upon the desired part of the assembling rails 7 between the last matrix M 35 thereon and the line packer 8 adjacent thereto.

Rigid with each of the rail plates 10 are the thin plates 30, whose right ends project beyond said rail plates and overhang the 40 ears 2^a of the foremost space band. The lower edges 30^a of these plates are beveled as shown.

When a stock of space bands are in the magazine, they will be supported by their 45 ears on the rails 13, and will lie in contact with one another. The forked lower ends of all of said space bands will straddle a fixed rail 35, and will be to the left of an upwardly projecting toe 34 fixed to said rail. 50 This toe is in such a position that the foremost space band must occupy the inclined position shown in Figs. 1, 2 and 5, at which time the upper end of said space band will engage the adjacent face of the thin upper 55 part 17^e of the slide 17. The engagement of the foremost space band with this slide, and with this toe prevents it, and all of the other space bands, from sliding off of the supporting rails 13. Now, as the slide 17 is 60 moved up, carrying the lifters 16 with it, the horizontal ends 16^a of said lifters will engage with the ears on the foremost space band, and will lift it, thereby carrying its lower end above the toe 34. As said lifters 65 go up, the inclined surfaces 16^b thereon will

engage the ears of the second space band, and will push it and all of the other space bands to the left in said magazine; and this will result in moving the upper end of the second space band out of contact with the 70 upper end of the foremost space band. Therefore, when the foremost space band has been lifted to free its lower end from the restraining influence of the toe 34 this space band will be freed from all restraint tending 75 to hold it in the inclined position, and therefore its lower end will swing to the right into the vertical position shown in Fig. 2. As the lifters continue to move up, the ears of this space band will be carried 80 into contact with the inclined surfaces 30^a on the plates 30, and thereby said space band will be pushed to the right until its ears are pushed off of the horizontal upper ends of the lifters. Thereupon this space band being freed from all restraint will fall vertically downward through the groove 17^d in slide 17, and onto the assembling rail 7 between the last matrix M thereon and the usual line packer 8. When the slide 17 is 90 now moved down to its former position, all of the space bands upon the rails 13 will move by gravity to the right, and the foremost of these space bands will take the same position which was formerly occupied by the 95 space band just released.

In the construction shown, the slide 17 is formed with ears 17^f which pass through a vertical slot 25^a in the cover plate 25. These ears carry a rod 17^e with which the forked 100 end of a pivoted lever 36 engages. By actuating this lever by any suitable means this slide is moved up and down as required. It is to be understood, however, that this particular mechanism for imparting to the 105 slide and the lifters thereon the required up and down movement is not at all essential to the present invention. Any other means for doing this may be employed.

Having described my invention, I claim: 110

1. In space band releasing mechanism, the combination of a space band magazine having inclined rails on which the ears of the space bands are suspended, vertically movable lifters adapted to engage the lower edges of the foremost space band, and plates having inclined faces adapted to engage the ears of the space bands as they are being moved up and to thereby push the space band away from the rails and off of said 115 lifters.

2. In space band releasing mechanism, the combination of a space band magazine having inclined rails on which the ears of the space bands are suspended, two vertically movable lifter bars having at their upper ends horizontal surfaces which normally lie beneath the ears on the foremost space band in the magazine and having beveled surfaces 125 which normally lie beneath the ears of the 130

second space band in the magazine, means for moving said bars simultaneously up and down, and means to push the foremost space bar away from said rails and off of said lifters.

3. In space band releasing mechanism, the combination of a space band magazine having inclined rails on which the ears of the space bands are suspended, two vertically movable lifter bars having at their upper ends horizontal surfaces which normally lie beneath the foremost matrix in the magazine and having beveled surfaces which normally lie beneath the ears of the second space band in the magazine, means for moving said bars simultaneously up and down, and plates having inclined lower surfaces which overhang the ears of the foremost space band and act to push its said ears off of said lifters as said foremost space band is being moved up.

4. In space band releasing mechanism, the combination of a space band magazine having inclined rails on which the ends of the ears of the space band are suspended, said rails having thin extensions beyond which the ears of the space bands may project, lifters having horizontal upper ends which lie normally beneath those parts of the ears of the foremost matrix which project beyond said rail extensions, and having beveled surfaces which normally lie beneath the corresponding parts of the ears of the second space band, and means for pushing the foremost matrix away from said rails and off of the horizontal ends of the lifters.

5. In space band releasing mechanism, the combination of a space band magazine having inclined rails on which the ends of the ears of the space band are suspended, said rails having thin extensions beyond which the ears of the space bands may project, lifters having horizontal upper ends which lie normally beneath those parts of the ears of the foremost matrix which project beyond said rail extensions, and having beveled surfaces which normally lie beneath the corresponding parts of the ears of the second space band, there being two plates having

beveled lower surfaces which overhang corresponding parts of the ears of the foremost space band and which act on said ears as said space band is being lifted to push the ears off of said lifters.

6. In space band releasing mechanism, the combination of a space band magazine having downwardly inclined rails on which the ears of the space bands are suspended, a vertically movable slide formed with an undercut groove in that face which is toward said rails, the said slide being so arranged that the upper ends of the overhanging vertical flanges which are necessarily produced by the forming of said undercut groove lie normally beneath the ears of the foremost space band in the magazine, and means for pushing said space band away from said rails to carry its ears off of said flanges and into said undercut groove.

7. In space band releasing mechanism, the combination of a space band magazine having downwardly inclined rails on which the ears of the space bands are suspended, a vertically movable slide formed with an undercut groove in that face which is toward said rails and with inwardly turned vertical flanges which form the side walls of said undercut groove, and having a thin upper end above said groove, the inwardly turned flanges of said undercut groove having on their upper ends horizontal surfaces which lie below the ears of the foremost space band in the magazine, and inclined surfaces which lie beneath the ears of the second space band in said magazine, a toe in the path of the lower ends of the space bars as they move to the releasing position, and inclined plates which overhang the ears of the foremost space band, and are engaged by said ears as the space band is lifted.

In testimony whereof, I hereunto affix my signature in the presence of two witnesses.

DAVID PETRI-PALMEDO.
